United States Patent Office.

GEORGE R. GARDINER, OF WESTERLY, RHODE ISLAND, ASSIGNOR TO HIMSELF AND BENJAMIN W. BENTLEY, OF SAME PLACE.

Letters Patent No. 70,543, dated November 5, 1867.

IMPROVEMENT IN CONDENSERS FOR CARDING ENGINES.

The Schedule referred to in these Letters Patent and making part of the same,

TO ALL WHOM IT MAY CONCERN:

Be it known that I, GEORGE R. GARDINER, of Westerly, in the county of Washington, and State of Rhode Island, have invented a new and improved Means for Depriving Wool and other Fibrous Substances of Electricity during the Carding and Condensing of the same; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim, and desired to have secured to me by Letters Patent.

In the manufacture of goods from wool, and some other fibrous substances, much difficulty is experienced by the development of electricity during the carding and condensing of the stock, or the forming of the same into ropings. The electricity thus developed very frequently deranges the condensing operation, causing the ropings to adhere to and wind around the cylinders of the condenser, and even the ropings, if they leave the condenser entire, are frequently broken by a strong current of electricity, which passes around in front of the condenser.

My invention consists in certain means employed for preventing the development of electricity during the carding and condensing operation, whereby a great amount of stock is prevented from being wasted, and the carding and condensing operation greatly expedited. In the accompanying sheet of drawings—

Figure 1 is a side sectional view of a condenser provided with my invention, taken in the line *x x*, fig. 2.

Figure 2, a horizontal section of the same, taken in the line *y y*, fig. 1.

Similar letters of reference indicate like parts.

A represents the frame of a condenser, and B the cylinders thereof. These may be arranged in the usual or any proper manner, and therefore do not require a special description. C represents a hollow roller, constructed of thin sheet metal, and rotated by gears or a belt from any convenient cylinder of the condenser. The direction of the rotation of the cylinders and roller is indicated by the arrows in fig. 1, the ropings, designated by *a*, passing from the front cylinders of the condenser underneath the rollers C, and in contact with the latter. Only one of these rollers C is shown in fig. 1, but the upper cylinders B are to be supplied with one placed in the same relative position as the lower one, which is shown. These hollow rollers are supplied, say about two-thirds filled, with a composition consisting of fire-clay, ordinary brick, or potters' clay, and granite dust, mixed with steel dust. The granite and steel dust may be obtained, mixed about in proper proportion, from granite quarries, the dust from the drill-holes containing the requisite amount of steel, which is worn off from the drills. The two different clays, and the granite and steel dust combined, are used in about equal proportions. These rollers C, charged with the composition described, effectually prevent the development of electricity; at least none is apparent to affect the ropings, which pass from the condenser without any impediment whatever. D represents a frame, in which the cylinders E are placed, on which the ropings are wound. Guide-bars F are also placed on this frame, having metal staples or loops *b* in them, through which the ropings *a* pass. These guide-bars are a short distance in front of the condenser, and the ropings *a* are frequently much swayed or moved laterally by a strong current of electricity which passes around the front of the condenser, between it and frame D. The end or outside ropings are most affected by it, and are often broken, occasioning considerable embarrassment and loss of stock. In order to avoid this, I attach guards G to each guide-bar F, one near each end of the same, said guards being constructed of sheet metal or other suitable material, and placed in line with the ropings. These guards G serve to shield the ropings and break any currents of electricity or draughts of air that may pass between the condenser and frame D.

I would remark that instead of having the rollers C hollow, and filled with the composition, they may be made solid, and the composition applied to their exterior, and secured or made to adhere thereto by any proper means. Either way would answer equally well.

Having thus described my invention, I claim as new, and desire to secure by Letters Patent—

1. The roller C, one or more, made either hollow or solid, and charged or covered with the composition herein described, or its equivalent, and placed on a condenser, in relative position with the cylinders B thereof, substantially in the manner as and for the purpose set forth.

2. The guards G, attached to the guide-bars F on frame D, and arranged in relation with the ropings *a* substantially as and for the purpose specified.

GEORGE R. GARDINER.
